UNITED STATES PATENT OFFICE.

PETER E. SNOW, OF DENVER, COLORADO, ASSIGNOR TO ADA E. SNOW, OF DENVER, COLORADO.

MEANS FOR CALKING PIPE-JOINTS.

No. 856,106.

Specification of Letters Patent.

Patented June 4, 1907.

Application filed April 2, 1906. Serial No. 309,453.

To all whom it may concern:

Be it known that I, PETER E. SNOW, a citizen of the United States, residing in the city and county of Denver and State of Colorado, have invented certain new and useful Improvements in Means for Calking Pipe-Joints; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in means for calking pipe joints.

My object is to do away with the old means of calking and substitute what I term a calking ring consisting preferably of lead adapted to be interposed in a cold state between the telescoping extremities of the pipe ends to be joined and forced therein in such a manner as to make a perfectly tight joint.

Heretofore so far as I am aware these joints have been formed by placing hemp, oakum or similar vegetable substance in the first instance between the two overlapping ends and after forcing the same tightly in place, molten lead is applied above the oakum whereby the space between the two ends to be joined is filled.

The object of using the oakum or similar material is to prevent the molten lead from escaping by running out between the pipe ends. The oakum or other vegetable packing not only makes an insecure support for the lead, but in time it decays with the result that the joint leaks. My improved means for forming these joints is not only much 35 more simple and less troublesome to use, but makes a permanent and absolutely secure joint, being one that will last as long as the pipe 6, thus obviating the necessity of renewing the joint at intervals.

40 Having outlined my improvement together with some of its advantages, I will proceed to describe the same in detail reference being made to the accompanying drawing in which is illustrated an embodiment 45 thereof.

In this drawing, Figure 1 is a detail view in side elevation of what I term my improved calking ring. Fig. 2 is a top plan view of the same. Fig. 3 is a section taken

on the line 3—3 Fig. 2. Fig. 4 is a sectional view of the bell end of a piece of iron pipe. Fig. 5 is a similar view of the opposite end, adapted to enter the bell end of the other pipe member in forming a joint. In Fig. 5 the calking ring is shown applied to the joint 6c but on a much larger scale than in Figs. 1 to 3 inclusive. Fig. 6 is a sectional view of the pipe ends shown in the assembled relation and after the joint is completed by the use of my improvement. 65

The same reference characters indicate the same parts in all the views.

Let the numeral 5 designate one pipe section and 6 the other section. The section 5 is provided with an enlarged or bell extremity 7 adapted to receive the extremity of the opposite pipe section 6 after the calking ring 8 is applied thereto. The section 6 is usually provided with a slight circumferential reinforcement or collar 9 forming a shallow 75 shoulder a short distance from the end of the pipe.

My improved calking ring is originally of the construction shown in Figs. 1 and 2. Let the numeral 10 designate the ring in its 80 entirety. This ring as originally molded is provided with a cylindrical base 12 and an upper portion 13 somewhat enlarged and provided with alternating interior and exterior longitudinally disposed grooves 14. 85 The ring is originally provided with these grooves so that afterward its circumference may be reduced by hammering it toward the pipe 6 whereby it is caused to assume the position shown in Fig. 5. As the grooved portion 90 of the ring is reduced in circumference by compression or hammering, the metal will gradually fill up the grooves at least to a certain extent.

In applying the calking ring to the pipe 95 member 6, the part 12 of the ring is applied to the shouldered or reinforced part 9 of the pipe, the part 12 being preferably made of a size to fit or approximately fit this part of the pipe. When the ring is first applied the upper or grooved portion 13 stands out from the body of the pipe 6. The operator then hammers the portion 13 toward the pipe until it is caused to fit the same closely. The extremity of the pipe 6 equipped with the 105 calking ring when in the position shown in Fig. 5, is inserted in the bell extremity 7 of the pipe member 5. A calking iron is then

5 applied to the outer exposed edge of the calking ring and the latter is forced inwardly between the two telescoping pipe extremities until the cold lead is caused to assume the 10 position approximately shown in Fig 6 making a perfectly tight joint, and one that is exceedingly durable.

15 It sometimes happens that the sewer pipe sections are not of perfectly regular formation. In other words when the member 6 is inserted in the bell end of the member 5, the edge of the pipe 6 while touching the shoulder of the bell a portion of the distance may not be engaged the entire distance owing to the 20 said irregularity. My improved calking ring is adapted to overcome this difficulty and make a perfectly tight joint as well where the edge of the pipe 6 does not engage the shoulder of the bell as where it does so engage. 25 This feature is illustrated in Fig. 6 in which the pipe 6 is shown engaging the shoulder of the bell on the lower side of the view, while it is separated therefrom but filled with the calking ring on the upper side of the view.

30 25 Attention is called to the fact that the grooves of the ring facilitate both expansion and contraction of the same and may be arranged in any suitable manner.

Having thus described my invention, what 35 I claim is:

1. A calking ring having a cylindrical base and an expanded upper portion provided with longitudinally disposed grooves.

2. A calking ring having a cylindrical portion and an enlarged portion having the shape of a frustum of a cone, the frustum-shaped part being provided with exteriorly and interiorly alternating V-shaped longitudinally disposed grooves.

3. A calking ring having one portion larger than the other portion, the larger portion being provided with longitudinally disposed grooves to facilitate the reduction of the

ring's diameter by inward pressure or hammering.

4. A calking ring composed of lead having a plain base portion and a frustum-shaped grooved portion for the purpose set forth. 45

5. In means for forming pipe joints, the combination of the pipe sections to be joined, one having a bell end and the other a reduced end adapted to enter the bell end, and an interposed soft metal calking ring, provided with grooves to facilitate expansion and contraction. 50

6. In a pipe joint, the combination of the two pipe sections to be joined, and an interposed soft metal calking ring which forms the exclusive packing for the joint, said ring having grooves for the purpose set forth. 60

7. A pipe joint composed of the two pipe sections, one having an enlarged or bell extremity and the other a shouldered extremity adapted to enter the bell extremity, and a cold soft metal calking ring interposed between the pipe ends to be joined and packed tightly in place, the said ring having grooves for the purpose set forth. 65

8. A soft metal calking ring provided with grooves for the purpose set forth. 70

9. A soft metal calking ring provided with longitudinally disposed grooves.

10. A soft metal calking ring provided with interior and exterior longitudinally disposed grooves. 75

11. A soft metal calking ring provided with longitudinally disposed grooves arranged both interiorly and exteriorly, but in staggered relation on the two opposite surfaces. 80

In testimony whereof I affix my signature in presence of two witnesses.

PETER E. SNOW.
